STEAM GENERATOR

Walter Gustav Noack, Baden, Switzerland, assignor to Aktiengesellschaft Brown Boveri & Cie, Baden, Switzerland, a joint stock company of Switzerland

Application May 20, 1930, Serial No. 453,941, and in Germany May 31, 1929

14 Claims. (Cl. 122—31)

This invention relates to steam generators, and it has particular relation to injection steam generators as described, for instance, in my co-pending application, Serial No. 268,493 which 5 matured into Patent 1,817,419. In such steam generators a small quantity of steam, called exciter steam, is superheated and applied to water, for instance, by injection of one medium into the other, to evaporate the water by the 10 superheat of the admitted steam and producing thereby an enlarged quantity of steam; the so-obtained larger quantity of steam is again superheated and utilized to convert a further quantity of water into steam, thus further increasing 15 the amount of available steam; and this process is successively repeated until the required quantity of steam is generated.

Among the objects of the present invention is the provision of an improved steam generator 20 of the foregoing type having special arrangements for securing efficient and desirable operating conditions at no load, as well as high load operation.

The foregoing and other objects of the invention 25 will be apparent from the following description, reference being made to the accompanying drawing which illustrates diagrammatically one embodiment of the invention.

As shown in the drawing, the multi-stage 30 injection steam generator comprises a reservoir 4 holding water in the bottom part and a quantity of steam under pressure in the top part. Feed water is suitably supplied to the reservoir 4 by a feed water line 5 through a water pre- 35 heater 5a which preheats the water before it is delivered to the reservoir. Included in the feed water pipe 5 is also a valve 5b actuated by a regulating device 5c which is connected to the steam space in the reservoir 4 to vary the 40 admission of feed water to the reservoir depending on the pressure therein, as will be explained hereafter.

To generate steam a small quantity of steam 45 is drawn by steam pump 6 from reservoir 4 and forced under pressure through a first superheater 7 into a first vaporizer 8. The vaporizer 8 is supplied with water from the reservoir 4 by means of a water pump 9 which forces water through a delivery line 11 and discharges 50 it in the vaporizer 8 in the form of a spray. The steam from the superheater 7 and the water from the delivery line 11 are thus brought into intimate contact, vaporizing a large quantity of water and producing a large quantity 55 of wet steam. Excessive injection water flows

back to the reservoir 4 from the vaporizer 8 through a return line 12.

The increased quantity of wet steam in vaporizer 8, being under the pressure of the steam pump 6, is forced from the vaporizer 8 through 60 a second superheater 13, where it is again superheated, into a second vaporizer 14 where the superheated steam converts additional water from line 11 into steam. This process is repeated in each of the successive vaporizer vessels 65 17 and 18 until the required quantity of steam is generated in the last vaporizer 19 from where the wet steam flows through a main superheater 21 and outlet valve 22 to the steam consuming devices. Thus, a very small quantity of 70 excitation steam from the reservoir 4 is sufficient to produce a large quantity of steam of such pressure as may be desired. The heat is supplied to the superheater coils 13, 16, 18, 21 by the hot combustion gases passing through gas 75 duct 3 in which the coils are mounted, the reservoir 4 being outside the duct. To initially start the operation, an auxiliary boiler 1, heated by the hot combustion gases in duct 3, is provided to produce an initial amount of steam 80 which is delivered through heating coil 2 to the steam space of reservoir 4 for starting the vaporization process in the series of vaporizer stages. The pressure of this exciter boiler 1 may be made sufficiently large to force the 85 steam flow through the several stages, in which case pump 6 would not be necessary, but operation with a pump is preferable, because under normal conditions reservoir 4 has always enough steam to start operation. For normal operation 90 95 the steam generated by the vaporizer stages is made about sufficient to supply the normal load.

The reservoir is utilized as a buffer or storer for taking care of excess steam demand or over-loads, and of excess steam generation by the vaporizer stages when the steam demand is below normal. This is effected by the provision of a bypass conduit with non-return valve 23 permitting steam flow from the outlet side of the main superheater 21 (before shut-off valve 100 22) to the water space of reservoir 4, and a bypass conduit with a non-return valve 24 permitting steam flow from the steam space of the reservoir 4 to the inlet of the main superheater 21, the valves opening and permitting flow of 105 steam when the pressure on the inflow side is excessive. Under the normal operating condition, the pressure of steam reservoir 4 is substantially the same as that at the discharge end 110 of the superheater 21 and so that non-return

valve 24 is closed, and the pressure at the main outlet valve 22 has a valve at which non-return valve 23 stays closed.

If the steam consumption suddenly increases, 5 the pressure in the final superheater 21 will drop below that of the reservoir 4 and the non-return valve 24 will be opened by the higher pressure on the reservoir side thereby permitting wet steam to flow from the reservoir 4 10 directly through the superheater 21 to the point of consumption.

If the steam consumption decreases, the total amount of steam generated will increase the steam pressure in the superheater 21 above that 15 in the reservoir 4 and the non-return valve 23 will open to permit a return of the excess superheated steam to the water space of reservoir 4 in which it is condensed. When the steam generator is being shut down by closing 20 valve 22, or when the supply is greatly in excess of the demand, in either of which cases large quantities of steam are returned through the non-return valve 14 to the container 1, an excessive pressure (blowing off) in the latter may 25 be avoided by the supply of excess feed water to the container. Since in comparison with ordinary boilers the container operates with greatly varying water levels, the level of the water in normal operation, will usually be kept relatively low and when closing down or during 30 periods of very low demand a large quantity of feed water will be introduced which condenses the excess steam. The extra feed water, in the same way as the normal feed water, is supplied 35 by feed water pipe 5 through the water preheater 5a in the flue duct 2 to the container 1. The admission of excess feed water is automatically regulated by the pressure regulator 5c which controls the feed regulator 5b to supply 40 more water to the container 1 when a predetermined pressure in the said container is exceeded. The regulation of the feed water in normal operation is effected in the usual manner by a regulator dependent on the alteration 45 of water level in the container.

Although but one embodiment of the present invention has been illustrated and described, it will be apparent that various changes and 50 modifications may be made therein without departing from the spirit of the invention or from the scope of the appended claims.

The invention claimed is:

1. In a steam generating installation, a reservoir for holding preheated water and steam, a pump connected with said reservoir to withdraw steam therefrom, a preliminary superheater receiving the steam from said pump, a primary vaporizer receiving the steam from said superheater, a plurality of secondary superheaters, a plurality of secondary vaporizers, said secondary superheaters and said secondary vaporizers being connected in series with said primary vaporizers, means connected with said reservoir for supplying water to all of said vaporizers, a final superheater receiving and heating the steam from all of said vaporizers, and means connecting the steam space of said reservoir directly with the inlet side of said final superheater during periods of increased demand for steam.

2. In a steam generating installation, a reservoir for holding preheated water and steam, a pump connected with said reservoir to withdraw steam therefrom, a preliminary superheater receiving the steam from said pump, a primary vaporizer receiving the steam from said super-

heater, a plurality of secondary superheaters, a plurality of secondary vaporizers, said secondary superheaters and said secondary vaporizers being connected in series with said primary vaporizer, means connected with said reservoir for supplying water to all of said vaporizers, a final superheater receiving and heating the steam from all of said vaporizers, and means connecting the outlet side of said final superheater directly with the water containing space of said reservoir during periods of decreased demand for steam.

3. In a steam generator, a steam generating circuit including a reservoir for holding preheated water and steam water from the said preheater, a pump connected with said reservoir to withdraw steam therefrom, a preliminary superheater receiving the steam from said pump, a primary vaporizer receiving the steam from said superheater, a plurality of secondary superheaters, a plurality of secondary vaporizers, said secondary superheaters and said secondary vaporizers being connected in series with said primary vaporizers, means connected with said reservoir for supplying water to all of said vaporizers, and a final superheater receiving and heating the steam from all of said vaporizers to the temperature desired for use; and a steam supply control circuit including a non-return valve for passing steam from the steam space of said reservoir directly into said final superheater during periods of increased demand for steam, and a non-return valve connecting the outlet side of said final superheater directly with the water containing space of said reservoir during periods of decreased demand for steam.

4. In a steam generator system, a reservoir for holding preheated water and steam, a main superheater having an inlet and an outlet, an injection steam vaporizer connected between the steam space of said reservoir and the inlet of said main superheater, said vaporizer comprising a vessel having a water inlet for supplying water to the vessel, superheater tubes connected between the reservoir and said vessel arranged to superheat steam received from said reservoir and discharge it in superheated condition into the vessel to vaporize water supplied thereto, and a steam outlet for delivering the resultant steam in said vessel into said main superheater, means associated with said reservoir to produce a steam flow from the reservoir through the vaporizer to the main superheater, generating in the vaporizer additional steam joining said flow, a bypass conduit connecting the steam space of said reservoir to the inlet side of said main superheater, a bypass conduit connecting the water space of said reservoir to the outlet side of said superheater, and valve means associated with said conduits arranged to permit flow of wet steam from the reservoir through its conduit to the main superheater and flow of superheated steam from said superheater to the water space of said reservoir depending on the pressure conditions in the system.

5. In a steam generator system, a reservoir for holding preheated water and steam, a main superheater having an inlet and an outlet, an injection steam vaporizer connected between the steam space of said reservoir and the inlet of said main superheater, said vaporizer comprising a vessel having a water inlet for supplying water to the vessel, superheater tubes connected between the reservoir and said vessel arranged to superheat steam received from said reservoir and discharge it in superheated condition into the

- vessel to vaporize water supplied thereto, and a steam outlet for delivering the resultant steam in said vessel into said main superheater, means associated with said reservoir to produce a steam flow from the reservoir through the vaporizer to the main superheater, generating in the vaporizer additional steam joining said flow, a bypass conduit connecting the steam space of said reservoir to the inlet side of said main superheater including valve means to permit flow of wet steam from the reservoir to the main superheater only in response to lower pressure at the superheater inlet than a corresponding pressure in said reservoir, and a bypass conduit connecting the water space of said reservoir to the outlet side of said superheater including valve means to permit flow of superheated steam from said superheater to the water space of said reservoir only in response to higher pressure at the superheater outlet than a corresponding pressure in said reservoir.
6. In a steam generator system, a reservoir for holding preheated water and steam, a main superheater having an inlet and an outlet, an injection steam vaporizer connected between the steam space of said reservoir and the inlet of said main superheater, said vaporizer comprising a vessel having a water inlet for supplying water to the vessel, superheater tubes connected between the reservoir and said vessel arranged to superheat steam received from said reservoir and discharge it in superheated condition into the vessel to vaporize water supplied thereto, and a steam outlet for delivering the resultant steam in said vessel into said main superheater, means associated with said reservoir to produce a steam flow from the reservoir through the vaporizer to the main superheater, generating in the vaporizer additional steam joining said flow, conduit means including a non-return valve opening in response to decrease of the pressure of the steam supply connecting the steam space of the reservoir to the inlet of said superheater to supply wet steam from the reservoir to the superheater, and conduit means including a non-return valve opening in response to excess of steam supply connecting the outlet side of the superheater to the water space of the reservoir causing superheated steam to flow from the superheater to the water space of the reservoir.
7. In a steam generator system, a reservoir for holding preheated water and steam, a main superheater having an inlet and an outlet, an injection steam vaporizer connected between the steam space of said reservoir and the inlet of said main superheater, said vaporizer comprising a vessel having a water inlet for supplying water to the vessel, superheater tubes connected between the reservoir and said vessel arranged to superheat steam received from said reservoir and discharge it in superheated condition into the vessel to vaporize water supplied thereto, and a steam outlet for delivering the resultant steam in said vessel into said main superheater, means associated with said reservoir to produce a steam flow from the reservoir through the vaporizer to the main superheater, generating in the vaporizer additional steam joining said flow, and a bypass conduit connecting the water space of said reservoir to the outlet side of said superheater including valve means to permit flow of superheated steam from said superheater to the water space of said reservoir only in response to higher pressure at the superheater outlet than a corresponding pressure in said reservoir.
8. In a steam generator system, a reservoir for holding preheated water and steam, a main superheater having an inlet and an outlet, a multi-stage injection steam vaporizer connected between the steam space of said reservoir and the inlet of said main superheater, said vaporizer comprising a plurality of serially arranged vaporizer stages, each of said stages comprising a vaporizer vessel having a water inlet for supplying water to the vessel, superheater tubes arranged to superheat received steam and discharge it in superheated condition into the vessel to vaporize water supplied thereto, and a steam outlet for delivering the resultant steam in said vessel, the steam outlet of the vaporizer vessel of each stage being connected to the inlet of the superheater tubes of the following stage, means associated with said reservoir to produce a steam flow from the reservoir through the successive stages to the main superheater, generating in each stage additional steam joining said flow, a bypass conduit connecting the steam space of said reservoir to the inlet side of said main superheater, a bypass conduit connecting the water space of said reservoir to the outlet side of said superheater, and valve means associated with said conduits arranged to permit flow of wet steam from the reservoir through its conduit to the main superheater, and flow of superheated steam from said superheater to the water space of said reservoir depending on the pressure conditions in the system.
9. In a steam generator system, a reservoir for holding preheated water and steam, a main superheater having an inlet and an outlet, a multi-stage injection steam vaporizer connected between the steam space of said reservoir and the inlet of said main superheater, said vaporizer comprising a plurality of serially arranged vaporizer stages, each of said stages comprising a vaporizer vessel having a water inlet for supplying water to the vessel, superheater tubes arranged to superheat received steam and discharge it in superheated condition into the vessel to vaporize water supplied thereto, and a steam outlet for delivering the resultant steam in said vessel, the steam outlet of the vaporizer vessel of each stage being connected to the inlet of the superheater tubes of the following stage, means associated with said reservoir for normally maintaining a higher pressure at the inlet side of said multi-stage vaporizer than at the outlet side thereof to produce a steam flow from the reservoir through the successive stages to the main superheater, generating in each stage additional steam joining said flow, conduit means including a non-return valve opening in response to insufficient steam supply connecting the steam space of the reservoir to the inlet of said superheater to supply wet steam from the reservoir to the superheater, and conduit means including a non-return valve opening in response to excess of steam supply connecting the outlet side of the superheater to the water space of the reservoir causing superheated steam to flow from the superheater to the water space of the reservoir.
10. In a steam generator system, a reservoir for holding preheated water and steam, a main superheater having an inlet and an outlet, a multi-stage injection steam vaporizer connected between the steam space of said reservoir and the inlet of said main superheater, said vaporizer comprising a plurality of serially arranged vaporizer stages, each of said stages comprising a vaporizer vessel having a water inlet for supplying water to the vessel, superheater tubes arranged to superheat received steam and discharge it in superheated condition into the vessel to vaporize water supplied thereto, and a steam outlet for delivering the resultant steam in said vessel, the steam outlet of the vaporizer vessel of each stage being connected to the inlet of the superheater tubes of the following stage, means associated with said reservoir to produce a steam flow from the reservoir through the successive stages to the main superheater, generating in each stage additional steam joining said flow, a bypass conduit connecting the steam space of said reservoir to the inlet side of said main superheater, a bypass conduit connecting the water space of said reservoir to the outlet side of said superheater, and valve means associated with said conduits arranged to permit flow of wet steam from the reservoir through its conduit to the main superheater, and flow of superheated steam from said superheater to the water space of said reservoir depending on the pressure conditions in the system.

- vaporizer stages, each of said stages comprising a vaporizer vessel having a water inlet for supplying water to the vessel, superheater tubes arranged to superheat received steam and discharge it in superheated condition into the vessel to vaporize water supplied thereto, and a steam outlet for delivering the resultant steam in said vessel, the steam outlet of the vaporizer vessel of each stage being connected to the inlet 10 of the superheater tubes of the following stage, means for supplying from the water space of said reservoir water to the water inlets of said vaporizer vessels and returning excess water in the vaporizer vessel to said reservoir, means associated with said reservoir for normally maintaining a higher pressure at the inlet side of said multi-stage vaporizer than at the outlet side thereof to produce a steam flow from the reservoir through the successive stages to the main superheater, generating in each stage additional steam joining said flow, a bypass conduit connecting the steam space of said reservoir to the inlet side of said main superheater including valve means to permit flow of wet steam from the reservoir to the main superheater only in response to lower pressure at the superheater inlet than a corresponding pressure in said reservoir, and a bypass conduit connecting the water space of said reservoir to the outlet side of said superheater including valve means to permit flow of superheated steam from said superheater to the water space of said reservoir only in response to higher pressure at the superheater outlet than a corresponding pressure in said reservoir.
11. In a steam generator system, a reservoir for holding preheated water and steam, a main superheater having an inlet and an outlet, a multi-stage injection steam vaporizer connected between the steam space of said reservoir and the inlet of said main superheater, said vaporizer comprising a plurality of serially arranged vaporizer stages, each of said stages comprising a vaporizer vessel having a water inlet for supplying water to the vessel, superheater tubes arranged to superheat received steam and discharge it in superheated condition into the vessel to vaporize water supplied thereto, and a steam outlet for delivering the resultant steam in said vessel, the steam outlet of the vaporizer vessel of each stage being connected to the inlet of the superheater tubes of the following stage, means associated with said reservoir to produce a steam flow from the reservoir through the successive stages to the main superheater, generating in each stage additional steam joining said flow, a bypass conduit connecting the steam space of said reservoir to the inlet side of said main superheater including valve means to permit flow of wet steam from the reservoir to the main superheater only in response to lower pressure at the superheater inlet than a corresponding pressure in said reservoir, and a bypass conduit connecting the water space of said reservoir to the outlet side of said superheater including valve means to permit flow of superheated steam from said superheater to the water space of said reservoir only in response to higher pressure at the superheater outlet than a corresponding pressure in said reservoir.
12. In a steam generator system, a reservoir for holding preheated water and steam, a main superheater having an inlet and an outlet, a multi-stage injection steam vaporizer connected between the steam space of said reservoir and the inlet of said main superheater, said vaporizer comprising a plurality of serially arranged vaporizer stages, each of said stages comprising a vaporizer vessel having a water inlet for supplying water to the vessel, superheater tubes arranged to superheat received steam and discharge it in superheated condition into the vessel to vaporize water supplied thereto, and a steam outlet for delivering the resultant steam in said vessel, the steam outlet of the vaporizer vessel of each stage being connected to the inlet of the superheater tubes of the following stage, means associated with said reservoir for normally maintaining a higher pressure at the inlet side of said multi-stage vaporizer than at the outlet side thereof to produce a steam flow from the reservoir through the successive stages to the main superheater, generating in each stage additional steam joining said flow, a bypass conduit connecting the steam space of said reservoir to the inlet side of said main superheater including valve means to permit flow of wet steam from the reservoir to the main superheater only in response to lower pressure at the superheater inlet than a corresponding pressure in said reservoir, and a bypass conduit connecting the water space of said reservoir to the outlet side of said superheater including valve means to permit flow of superheated steam from said superheater to the water space of said reservoir only in response to higher pressure at the superheater outlet than a corresponding pressure in said reservoir.
13. In a steam generator system, a reservoir for holding preheated water and steam, a main superheater having an inlet and an outlet, a multi-stage injection steam vaporizer connected between the steam space of said reservoir and the inlet of said main superheater, said vaporizer comprising a plurality of serially arranged vaporizer stages, each of said stages comprising a vaporizer vessel having a water inlet for supplying water to the vessel, superheater tubes arranged to superheat received steam and discharge it in superheated condition into the vessel to vaporize water supplied thereto, and a steam outlet for delivering the resultant steam in said vessel, the steam outlet of the vaporizer vessel of each stage being connected to the inlet of the superheater tubes of the following stage, means for supplying from the water space of said reservoir water to the water inlets of said vaporizer vessels, means associated with said reservoir to produce a steam flow from the reservoir through the successive stages to the main superheater, generating in each stage additional steam joining said flow, a bypass conduit connecting the steam space of said reservoir to the inlet side of said main superheater including valve means to permit flow of wet steam from the reservoir to the main superheater only in response to lower pressure at the superheater inlet than a corresponding pressure in said reservoir, a bypass conduit connecting the water space of said reservoir to the outlet side of said superheater including valve means to permit flow of superheated steam from said superheater to the water space of said reservoir only in response to higher pressure at the superheater outlet than a corresponding pressure in said reservoir.

heater outlet than a corresponding pressure in said reservoir, and means for variably supplying feed water into said reservoir to condense excess steam flowing from the superheater to said reservoir.

14. In a steam generator system, a reservoir for holding preheated water and steam, a main superheater having an inlet and an outlet, a multi-stage injection steam vaporizer connected between the steam space of said reservoir and the inlet of said main superheater, said vaporizer comprising a plurality of serially arranged vaporizer stages, each of said stages comprising a vaporizer vessel having a water inlet for supplying water to the vessel, superheater tubes arranged to superheat received steam and discharge it in superheated condition into the vessel to vaporize water supplied thereto, and a steam outlet for delivering the resultant steam in said vessel, the steam outlet of the vaporizer vessel of each stage being connected to the inlet of the superheater tubes of the following stage, means for supplying from the water space of said reservoir water to the water inlets of said

vaporizer vessels, means associated with said reservoir to produce a steam flow from the reservoir through the successive stages to the main superheater, generating in each stage additional steam joining said flow, a bypass conduit connecting the steam space of said reservoir to the inlet side of said main superheater including valve means to permit flow of wet steam from the reservoir to the main superheater only in response to lower pressure at the superheater inlet than a corresponding pressure in said reservoir, a bypass conduit connecting the water space of said reservoir to the outlet side of said superheater including valve means to permit flow of superheated steam from said superheater to the water space of said reservoir only in response to higher pressure at the superheater outlet than a corresponding pressure in said reservoir, means for supplying feed water to said reservoir, and means for increasing the admission of feed water to said reservoir in response to increase of the pressure in said reservoir.
